UNITED STATES PATENT OFFICE.

CHARLES SEYMOUR, OF DEFIANCE, OHIO, ASSIGNOR TO THE DEFIANCE MACHINE WORKS, OF DEFIANCE, OHIO, A CORPORATION OF OHIO.

SPOKE-TENONING MACHINE.

SPECIFICATION forming part of Letters Patent No. 687,662, dated November 26, 1901.

Application filed May 7, 1901. Serial No. 59,133. (No model.)

To all whom it may concern:

Be it known that I, CHARLES SEYMOUR, a citizen of the United States, and a resident of Defiance, in the county of Defiance and 5 State of Ohio, have invented a new and Improved Spoke-Tenoning Machine, of which the following is a full, clear, and exact description.

The invention relates to woodworking machinery; and its object is to provide a new and improved spoke-tenoning machine designed for the use of spoke, wheel, and wagon manufacturers to dress the ends of the spokes to fit the mortise in the wheel-hub, the machine being comparatively simple and durable in construction, very accurate in operation to insure uniform work, and arranged to handle large and small spokes and to cut either a plain tenon or to completely tenon, 15 miter, and point a Sarven spoke during the passage of the spoke through the machine.

The invention consists of novel features and parts and combinations of the same, as will be fully described hereinafter and then pointed 20 out in the claims.

A practical embodiment of the invention is represented in the accompanying drawings, forming a part of this specification, in which similar characters of reference indicate corresponding parts in all the views.

Figure 1 is a front perspective view of the machine. Fig. 2 is a rear perspective view of the same. Fig. 3 is an enlarged end elevation of the same. Fig. 4 is a rear sectional elevation of the same on the line 4-4 in Fig. 3. Fig. 5 is a sectional plan view of the equalizing device for the spoke-guides, the section being on the line 5-5 in Fig. 4. Fig. 6 is an enlarged sectional plan view of part of the 35 feed-reel, the section being on the line 6-6 in Fig. 3. Fig. 7 is a similar view of another part of the feed-reel, the section being on the line 7-7 in Fig. 3. Fig. 8 is an enlarged front face view of a cutter-head for forming the 40 tenon-point and the miter on the inner end of the spoke at one operation. Fig. 9 is a sectional side elevation of the same on the line 9-9 in Fig. 8. Fig. 10 is a rear face view of the same. Fig. 11 is a front elevation of one 45 of the carriers for the miter-cutter. Fig. 12 is an enlarged inner face view of the cam for

adjusting the cutter-carriers. Fig. 13 is a side view of the spoke before forming the tenon, the point, and the miter. Fig. 14 is a like view of the finished spoke, and Fig. 15 55 is a plan view of the key-pinion for turning the cam and adjusting the miter-cutter of the cutter-head.

The tenoning-machine is mounted on a base A and a column A', secured on said base, and 60 the spokes to be formed at their inner ends B² with tenons B' (see Figs. 13 and 14) are moved over the rims C' C² of a stationary hood C by reel-arms D D' and fingers E, so as to pass the spokes between and along the 65 top guides F F' and the bottom guides F² F³, so that the inner ends of the spokes B² pass between cutter-heads G G' to form the tenons B', points B³, and the miters B⁴, (see Fig. 14,) the finished spokes finally dropping over the 70 rear ends of the bottom guides F² F³ upon a downwardly-inclined rack or chute X, from which the accumulated spokes are removed from time to time.

The reel-arms D D' are secured to the outer 75 faces of rim gear-wheels H H', mounted to turn on annular bearings C³, integral with the webs C⁴ for the rims C' C², said annular bearings C³ being arranged concentrically and spaced inwardly from said rims, as will 80 be readily understood by reference to Figs. 1, 6, and 7. The webs C⁴ are rigidly connected with each other by a hub-like bar C⁵, and the rims C' C² are provided with feet C⁶, bolted or otherwise fastened to the base A. 85 The rims C' C² are formed at the rear with cut-out portions C⁷ (see Fig. 4) for projecting the pinions I I' in mesh with the rim gear-wheels H H', respectively, said pinions I I' 90 being secured on a longitudinally-extending shaft I², having bearings C⁸ on said rims C' C², (see Figs. 4,) and also a bearing on the column A', as is plainly shown in Fig. 2. On one end of the shaft I² (see Fig. 2) is secured a gear-wheel I³, in mesh with a pinion I⁴, secured to an intermediate shaft I⁵, journaled in suitable bearings at the rear of the column A', and on said shaft I⁵ is secured a gear-wheel I⁶, in mesh with a pinion I⁷; fastened on a shaft I⁸, likewise journaled in suitable 95 bearings at the rear of the column A'. On the shaft I⁸ is mounted to rotate loosely a 100

pulley I⁹, connected by belt with other machinery for rotating said pulley, and the latter is adapted to be connected by a suitable friction-clutch I¹⁰ with the shaft I⁸ to rotate the latter whenever it is desired to run the machine. The friction-clutch I¹⁰ is under the control of the operator standing at the front of the machine, and for this purpose said friction-clutch is connected with a suitable shifting mechanism adapted to be worked by the foot of the operator, as indicated in Fig. 1, to shift the friction-clutch, and thereby the pulley I⁹ in or out of gear with the shaft I⁸. When the shaft I⁸ is rotated, then the above-described gearing rotates the pinions I I' and the gear-wheels H H' in unison to cause the arms D D' to move the spokes B over the rims C' C², it being understood that the attendant in charge of the machine places one spoke after another upon the rims C' C² in front of a pair of advancing arms D D', as will be readily understood by reference to Fig. 1. The arms D D' are secured to the outer faces of the respective gear-wheels H H', so that said arms project beyond the peripheral face of the rims C' C² to readily take hold of the spokes, as above mentioned, and shown in Figs. 1 and 3. The fingers E, previously mentioned, only operate in conjunction with the reel-arms D D', and a finger forms with the corresponding reel-arm a fork, between which is held the outer end of the corresponding spoke B. (See Fig. 3.) The fingers E have their inner ends provided with sleeves E', having polygonal bores engaging a correspondingly-shaped ring E², so that the fingers E can be adjusted on the ring according to the thickness of the spoke under treatment, the fingers then being secured in place on the ring by a set-screw E³. (See detail view, Fig. 7.) The ring E² is carried by pins D², attached to the inner portions of the reel-arms D', so that the peripheral face of the ring E² abuts against said pins, as is plainly indicated in Fig. 3, it being understood that every other arm D is preferably provided with such a pin; but each arm may carry one, if desired. One of the pins D² (see Figs. 3 and 6) is provided at its outer threaded portion with a nut D³ for engaging a washer E⁴ for clamping the ring E² in place against a collar D⁴ integral with the pin D², so that the ring E² is held in place for the time being, and when it is desired to adjust the machine for different-sized spokes then the nut D³ is simply loosened and the ring E² is turned on the pins D² to move the several fingers E nearer to or farther from the arms D', according to the thickness of the spoke. When the adjustment has been made, the nut D³ is screwed up to cause the washer E⁴ to clamp the ring E² in place, so that the several fingers stand the same distance spaced from the reel-arms D D'. It is expressly understood that the reel-arms D D' extend from the outer faces of the gear-wheels H H', and the latter are mounted in the space between the bearings C³ and the

70 rims C' C² to be completely out of sight and not interfere with the spokes as the latter are moved over the rims C' C² by the arms D D'. 70

In order to hold the gear-wheels H H' in position on the bearings, suitable retaining-plates C⁹ are secured to the bearings C³ and project over the faces of the gear-wheels, as is plainly indicated in Figs. 3 and 7. From 75 the foregoing it is understood that the driven gear-wheels H H', the arms D D', and the fingers E operate in conjunction with the stationary arms C' C² of the hood C and form the feed-reel of the machine for moving the 80 spokes between the guides F F' and between the cutter-heads. The guides F and F' extend transversely in vertical alinement one with the other, and said guides are formed or secured to guide-brackets F⁴ F⁵, projecting 85 sidewise from the guide-plates F⁶ F⁷, of which the plate F⁶ lies in front of the plate F⁷, (see Figs. 4 and 5,) and both are mounted to slide vertically in a guideway K, held vertically adjustable in guideways A² on the column A', 90 the vertical adjustment of the guideway K being made by the operator turning a screw-rod K', mounted to turn loosely in the plate K and screwing in the top of the column A'. (See Fig. 4.) The plates F⁶ and F⁷ are connected with each other and supported by an equalizing device for simultaneously moving the guides F F' from or toward each other to allow the guides to yield on any unevenness or roughness of the ends B² of the spokes B 100 and prevent binding of the spokes in the guides, the equalizing device also permitting of manually adjusting the guides by the operator to set the guides F F' for different sizes of spokes. 105

The equalizing device consists, essentially, of links L L', pivotally connected with the upper ends of guide-plates F⁶ F⁷, the links being also connected with a lever L², fulcrumed on a stud L³, secured to the upper end of the guideway K, said stud L³ being midway between the pivotal connections of said links L L' with said lever L², so that when the latter is rocked a simultaneous sliding motion is given to the guide-plates F⁶ F⁷ to move the guides F F' an 115 equal distance toward and from each other. By the operator turning the screw-rod K' the guideway K is moved up or down, so that bolt-plates F⁶ F⁷, their brackets F⁴ F⁵, and the guides F F' are moved bodily up or down 120 with the guideway K to bring said guides F F' in proper relation to the cutter-heads G G'. 125

On the rear end of the lever L² is swiveled a nut L⁴, in which screws a screw-rod L⁵, also screwing in a turnbuckle L⁶, to which is fastened one end of a spring L⁷, secured at its other end to the column A'. By the operator turning the screw-rod L⁵ the nut L⁴ is moved up or down to impart a swinging motion to the lever L², and thereby set the guides F F' 130 a desired distance apart, the distance corresponding to the thickness of the ends B² of the spokes to be operated upon by the machines. In case the ends B² are rough or

somewhat unequal the guides F F² readily yield, owing to the spring L⁷, connected with the screw-rod L⁵.

The guide F' is held on a bar N, carrying at its outer end a weight N' and fulcrumed at its inner end at N² on the arm O' of a cam O, bolted to the guideway K and moving with the same when the guideway is adjusted, as previously explained. The cam O extends in front of the guide-plates F⁶ F⁷ to hold the latter in position, as will be readily understood by reference to Figs. 3, 4, and 5. The fulcrum end of the bar N is provided with an upwardly-extending arm N³, through which extends loosely a bolt N⁴, secured in the arm O', the nut N⁵ of the bolt engaging the face of the arm N³, so that when the nut is adjusted the bar N and guide F' are swung up or down to bring the guide F' in proper position for the spokes. As the bar N is free to swing upward against the weight of the weight N', it is evident that the guide readily adjusts itself to any unevenness or roughness in the spokes. The guide F⁸ is located below the guide F' and is held transversely adjustable on a bracket P, held vertically adjustable on the inner face of the web C³ for the rim C². (See Figs. 2 and 4.)

The stop-plate Q for the inner ends of the spokes to abut against when the spokes are placed by the attendant in position on the rims C¹ C² extends transversely and parallel to the guide F² and somewhat at the left thereof, and this stop-plate Q is provided with a longitudinal rod Q', adjustably held in a bearing F⁹, secured to or formed on the top guide F, the rod Q' being secured in place by a setscrew Q² after the stop-plate is set to the proper position for the cutter-heads G G' to cut the tenon to the desired length. (See Fig. 4.) The cutter-heads G G' are alike in construction, and each is provided with a cutter-head body G², (see Figs. 8, 9, and 10,) on which are mounted a set of tenon-cutters R, a set of miter-cutters R', a set of pointing-cutters R², and a set of shoulder-cleaning cutters R³, all arranged in such a manner that when the end B² of a spoke B passes between the revolving cutter-heads G G' then said end is dressed and the tenons B', the points B³, the miters B⁴, and the shoulders B⁵ are all accurately formed at one operation. Each set of cutters consists, preferably, of two cutters, and the cutters R R² R³ are mounted in the usual manner on the body G², while the tenon-cutters R' are each adjustably secured on the inclined top S' of a carrier S by means of bolts R⁴, each carrier S being mounted to slide in guideways G³, formed radially on the face of the cutter-head body G². (See Figs. 8 and 9.) A bolt S², screwing in the carrier S and extending through an elongated slot G⁴ in the body G², serves to secure the carrier firmly in place after the carrier is adjusted in its guideways G³. On the face of each carrier S, at or near the inner end thereof, are formed segmental teeth S³ (see Figs. 9

and 11) in mesh with a spiral rib S⁴, formed on the inner face of a ring-shaped cam S⁵, mounted to turn on the hub of the body G², 70 the cam being held in position on the hub by a retaining-ring G⁶, as indicated in Figs. 8 and 9. The peripheral face of the cam S⁵ is provided with a gear-wheel S⁶, adapted to be engaged by a pinion S⁷ in the form of a key 75 having a handle S⁸, (see Fig. 15,) adapted to be set in the body G², as indicated in Fig. 8. When the key-pinion S⁷ is placed in position in one of the bearings, it is in mesh with the gear-wheel S⁶, and when the operator now 80 turns the handle S⁸ then the pinion S⁷ imparts a rotary motion to the gear-wheel S⁶ and the cam S⁵ and causes the spiral rib S⁴ thereof to move the carriers S simultaneously inward or outward, according to the direction in which 85 the key-pinion S⁷ is turned. Thus by the arrangement described the operator can move the carriers S, and consequently the tenon-cutters R', outward or inward to cut the ends B² and leave tenons of the desired thickness. 90 When the adjustment has been made, the operator simply removes the key-pinion S⁷ from the bearing G⁶, it being understood that when the adjustment has been finished and the bolts S² screwed up then the several parts are 95 securely locked in position on the cutter-head body G².

The cutter-head herein shown and described is not claimed in this application, but forms the subject-matter of a separate application filed July 16, 1901, Serial No. 68,485.

The cutter-heads G G' have their bodies G² secured on spindles G⁷ and G⁸, journaled in suitable bearings carried by saddles T T', vertically adjustable on suitable guideways carried by the column A', the adjustment of the saddles being accomplished by the attendant turning screw-rods T² T³, journaled in the column A' and engaging nuts on the saddles. A hand-wheel T⁴ is adapted to be locked to 110 either of the screw-rods T² or T³ to turn the same and move the corresponding saddle up or down to make the desired adjustment of the cutter-heads. On the spindles G⁷ G⁸ are secured pulleys U U', respectively engaged 115 by a drive-belt U², connected with other machinery, for imparting a rotary motion to the pulleys, the spindles, and the cutter-heads to revolve the latter for the purpose described. The belt U² also passes under a tightening-pulley U³, (see Figs. 1 and 2,) journaled on a slide U⁴, mounted to move vertically in suitable guideways on the column A', the slide U⁴ being adjustable vertically by suitable mechanism, preferably a rack and pinion, under the control of the attendant. (See Fig. 2.)

The shifting device for throwing the clutch I¹⁰ in or out of gear with the driven pulley I⁹ consists, essentially, of a shifting fork J', 130 (see Fig. 2,) secured on a rock-shaft J², journaled in the column A' and extending to the front thereof. On the front end of the rock-shaft J² is secured an arm J³, pivotally con-

nected with a rod J^4 , pressed on by a spring J^5 for normally holding the clutch I^{10} out of gear with the pulley. The rod is mounted to slide on a bearing or bracket J^6 , secured to the base A , and the free end of the rod is adapted to be engaged by a treadle J^7 , fulcrumed on the bracket J^8 and adapted to be pressed by the attendant's foot to throw the clutch in gear and rotate the shaft I^2 .

10. The operation is as follows: When the machine is in operation and the operator places a spoke B in position on the rims $C' C^2$ and the feed-reel arms $D D'$ and fingers E carry the spoke forward, then the ends B^2 of the 5 spoke abutting against the stop-plate Q are finally brought between the guides $F^2 F^3$ and between the cutter-heads $G G'$, so that the several cutters thereon form the tenon B' , the point B^3 , the miter B^4 , and the shoulders B^5 . 20. The finished spoke B is then pushed by the reel-arms $D D'$ along the rear ends of the guides $F^2 F^3$, and finally said arms and fingers move out of engagement with the spoke, and the latter is then pushed farther rear- 25 ward by the next following spoke until the spokes successively drop over the rear ends of the guides $F^2 F^3$ upon the chute X , pro- vided at its lower end with stop-pins X' for retaining the spokes on the chute. When a de- 30 sired number of spokes have accumulated in the chute, they are removed by the attendant.

From the foregoing it is evident that the various parts of the machine can be readily adjusted to dress spokes of different sizes, 35 shapes, and lengths, and to form tenons of the desired thickness and length, it being understood that the spokes are dressed uniformly and with great accuracy.

Having thus fully described my invention, 40 I claim as new and desire to secure by Letters Patent—

1. A woodworking-machine having a feed-reel provided with driven wheels having feed-arms, and stationary covers for said wheels 45 and forming a rest for a spoke as the latter is moved forward by said reel-arms, as set forth.

2. A woodworking-machine having a feed-reel provided with driven wheels and arms thereon, and covers for said driven wheels 50 and open at the faces carrying the arms, as set forth.

3. A woodworking-machine having a feed-reel provided with driven wheels and arms thereon, and covers for said driven wheels 55 and open at the faces carrying the arms, said covers forming a rest for a spoke as the latter is moved forward by the arms, as set forth.

4. A woodworking-machine having a feed-reel, consisting of driven inclosed gear-wheels, 60 and arms secured to the faces thereof and projecting outwardly, as set forth.

5. A woodworking-machine having a feed-reel, consisting of driven inclosed gear-wheels, arms secured to the faces thereof and project- 65 ing outwardly, a ring concentric with the gear-wheels and adjustably secured in the

arms of one of the gear-wheels, and fingers adjustably secured on said ring and spaced from the arms, to form with the latter forks for receiving the outer ends of the spokes, as 70 set forth.

6. A woodworking-machine having a fixed hood, annular bearings inside of the hood, and driven wheels mounted to turn on said bearings and having feed-arms projecting be- 75 yond the hood, as set forth.

7. A woodworking-machine having a fixed hood with an annular rim and internal bearings, gear-wheels mounted to turn on said bearings, and arms secured to the faces of the 80 gear-wheels and projecting beyond said rims, to carry the spoke along over said rims as their support, as set forth.

8. A woodworking-machine having a fixed hood with an annular rim and internal bear- 85 ings, gear-wheels mounted to turn on said bearings, arms secured to the faces of the gear-wheels and projecting beyond said rims, to carry the spoke along over said rims as their support, and driven pinions in mesh 90 with said gear-wheels through openings in said rims, as set forth.

9. A woodworking-machine having a fixed hood for the reel and forming a rest for the spokes as the latter are moved along by the 95 reel-arms, said hood having spaced annular rims, integral webs for the rims, and a connection between the webs, as set forth.

10. A woodworking-machine having a fixed hood for the reel and forming a rest for the 100 spokes as the latter are moved along by the reel-arms, said hood having spaced annular rims, integral webs for the rims, a connection between the webs, and an annular bearing inside of the hood and integral with the 105 webs, as set forth.

11. A woodworking-machine having a feed-reel provided with a driven gear-wheel, arms secured to one face thereof, a ring carried by said arms, and fingers adjustably secured on 110 said ring and extending in transverse alignment with said arms, as set forth.

12. A woodworking-machine having a feed-reel provided with a driven gear-wheel, arms secured to the face of the gear-wheel, pins on 115 sundry of said arms and arranged in a circle, a ring fitted against the inside of said pins, a clamping device for clamping the ring in place, and fingers on said ring and extending in line with said arms, as set forth. 120

13. A woodworking-machine having a feed-reel provided with a driven gear-wheel, arms secured to the face of the gear-wheel, pins on sundry of said arms and arranged in a circle, a ring fitted against the inside of said 125 pins, a clamping device for clamping the ring in place, fingers on said ring and extending in line with said arms, and means for adjustably securing said fingers in place on said ring, as set forth.

14. A woodworking-machine having top and bottom guides for a spoke, and an equalizing 130

- device connecting said guides with each other, to equally and simultaneously move the same toward or from each other, as set forth.
15. A woodworking-machine having top and bottom guides for spokes and mounted to slide, an equalizing device for moving the guides equally and simultaneously toward or from each other, said device consisting of links connected with the guides, and a lever connected with said links on opposite sides of its fulcrum, as set forth.
16. A woodworking-machine having top and bottom guides for spokes and mounted to slide, an equalizing device for moving the guides equally and simultaneously toward or from each other, said device consisting of links connected with the guides, a lever connected with said links on opposite sides of its fulcrum, and an adjusting device for said lever, as set forth.
17. A woodworking-machine having top and bottom guides for spokes and mounted to slide, an equalizing device for moving the guides equally and simultaneously toward or from each other, said device consisting of links connected with the guides, a lever connected with said links on opposite sides of its fulcrum, an adjusting device for said lever, and comprising a nut at one end of the lever, a screw-rod screwing in the nut, a spring, and a connection between the said screw-rod and said spring, as set forth.
18. A woodworking-machine having top and bottom guides for the spokes and mounted to slide, an equalizing device for moving the guides equally and simultaneously toward or from each other, said device consisting of links connected with the guides, a lever connected with said links on opposite sides of its fulcrum, and an adjustable guideway for said guides and carrying the fulcrum for said lever, as set forth.
19. The combination with the feed-reel for moving the spokes forward, of the stop-plate to engage the ends of the spokes, the top and bottom guides for the spokes, the equalizing device connecting said guides to move the same toward and from each other, and the cutter-heads to which the spokes are fed, as set forth.
20. The combination with the feed device having means for carrying the spokes forward, of the cover for the feed device forming a rest for the spokes as the latter are moved forward, top and bottom guides between which the spokes pass, and the driven cutter-heads for cutting the spokes, as set forth.
21. The combination with the driven wheels having means for feeding the spokes, and covers for said wheels forming a rest for the spokes as the latter are moved forward by the feeding means, of top and bottom guides between which the spokes pass, and driven cutter-heads for cutting the ends of the spokes, as set forth.
22. The combination with the driven wheels having feeding-arms for the spokes, and covers for said wheels forming a rest for the spokes as the latter are moved forward of a stop-plate against which one end of the spoke abuts, top and bottom guides between which the spoke passes, and the driven cutter-heads, as set forth.
23. The combination with the feed device for moving the spokes forward, and the cover for said feed device forming a rest for the spokes, as the latter are moved forward, of the stop-plate against which one end of the spoke abuts, top and bottom guides between which the spoke passes, the driven cutter-heads, and the chute at the rear of the bottom guides, as set forth.
24. In a woodworking-machine, the combination with the cutter-heads, of the top and bottom guides for the spokes, the guide-brackets to which the guides are connected, the guide-plates carrying the brackets, a vertically-adjustable guideway in which the guide-plates are mounted to slide vertically, and means for adjusting the guideway, to bring the guides in proper relation to the cutter-heads, as set forth.
- In testimony whereof I have signed my name to this specification in the presence of two subscribing witnesses.
